United States Patent Office.

JOHN B. JORDAN, OF AURORA, WISCONSIN.

Letters Patent No. 79,356, dated June 30, 1868.

IMPROVED CLEANING AND BORING-DEVICE.

The Schedule referred to in these Letters Patent and making part of the same.

TO ALL WHOM IT MAY CONCERN:

Be it known that I, JOHN B. JORDAN, of the town of Aurora, in the county of Waushara, and State of Wisconsin, have invented certain new and useful Improvements in Boring and Cleaning Wells; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to devices or apparatus for boring and cleaning out wells, and consists of an iron cylinder placed upon a shaft, which is provided with novel mechanical contrivances for boring and loosening the earth, and allowing the same to enter the cylinder, so that it can be conveniently removed from the well.

In the drawings—

Figure 1 is a perspective view.

Figure 2 is a perspective view, with a part of the cylinder broken away so as to show the interior arrangement; and

Figure 3 is a side view of the lower end of fig. 1, partly in section.

In constructing my apparatus, I make a metallic cylinder, A, of any required length and diameter, and of suitable strength, and attach to its upper end a bail, B, having a hole, a, in it, and two eyes, b, one on each side of this hole, as clearly shown in figs. 1 and 2. Near the lower end of the cylinder, I attach firmly a cross-bar, C, with a hole, d, in its centre, as shown in fig. 2.

Through the openings in the bail B and cross-bar C, I pass a shaft, D, and to the lower end of this shaft D, I attach or connect firmly two auger-lips, E, similar to those used in post-augers, and provide that portion of their peripheries extending from the line of their cutting-edges a short distance round, with a flange, F, made so as to stand parallel with the sides of the cylinder A, and a little outside of it, as shown in figs. 2 and 3. To the side of each lip E, just over the cutting-edge of the other, and just behind the flange F, I hinge a valve, e,

as shown in fig. 2.

To the end of the shaft D, below the lips E, I attach, in any suitable way to admit of its being removed at pleasure, an adjustable winged scraper, G. The wings e, I curve on their outer ends, and shape them generally as shown in figs. 1 and 3. Their shanks, f, fit into sockets g of the arms h of the scraper, which are provided with screws i, for holding them in place when adjusted as shown in figs. 1 and 3.

When desired for any purpose, I remove the scraper G, and attach a double-worm, H, for purposes hereafter explained.

The shaft D, I make in sections, which are connected together as the cylinder enters the well and follows the auger into the ground.

In boring a well, I use my device with or without the scraper G. Having attached cords to the eyes b, to connect with a windlass, I revolve in any suitable manner the shaft D. The lips E and their flanges F cut into the soil or ground which passes through the valves e, entering the cylinder A. As soon as the cylinder A is filled, or when desired, I elevate it by means of the windlass and cords, empty it, and repeat the operation as long as desired.

When a well is to be cleaned or enlarged, I attach the scraper G, adjusting its wings e as desired. As these wings are curved, when they revolve they will force or carry the earth under the cylinder, so that it can pass through the valves e into the cylinder, and thus be taken out.

Sometimes it is desirable to get ropes, chains, or other articles out of the bottom of the well. This I readily accomplish by attaching the double worm H to the lower end of the shaft D. This worm, as it revolves, fastens upon the articles, so that they may be removed from the well with the worm.

The shaft D revolves loosely in the bail B and cross-piece C, and as the flanges F cut the hole a little larger than the cylinder, the cylinder will keep close to the auger by its own gravity. In order, however, to prevent

the shaft D from going too far through the cylinder, under any circumstances, I place a collar, I, on it, just above the bail B. A pin or other suitable device may be used in place of a collar, if desired.

In this way I construct a cheap and convenient apparatus for safely, easily, and quickly boring or cleaning wells.

Some wells are small, or badly put up, or for other causes unsafe to enter. In these my apparatus can be used to great advantage. It is specially adapted for use in quicksand or soft mud, as the auger will enter it freely, and the loosened material will pass freely through the valves into the cylinder.

Having thus described my invention, what I claim, is—

1. An apparatus for boring and cleaning wells, consisting of the metallic cylinder A, shaft D, with auger-lips E, provided with flanges F and valves e, constructed and arranged to operate substantially as herein described.

2. In combination with the cylinder A, shaft D, with the auger-lips E, provided with flanges F and valves e, I claim the scraper G, with its adjustable wings or curved arms e, when constructed and arranged to operate substantially as herein described.

JOHN B. JORDAN.
